IRONING APPARATUS

Theodore R. Bush, Royal Oak, Mich., assignor to
 Borg-Warner Corporation, a corporation of Illinois

Application December 24, 1935, Serial No. 56,037

15 Claims. (Cl. 38—34)

This invention, in general, relates to ironing apparatus and has reference particularly to improvements in construction of ironing apparatus whereby a practical ironing apparatus of the 5 portable hand operated type may be constructed.

A principal object of the invention is to provide an improved form of portable hand operated ironing apparatus which is more efficient in operation, which is relatively light in weight so 10 that it is truly portable, which is simple in construction, which is easy and relatively simple to operate, which is adapted to be made under high production methods of manufacturing, and which is relatively inexpensive to manufacture.

Another object of the invention is to provide 15 a novel form of hand operated ironing apparatus in which a single lever is utilized for controlling the different operations of the apparatus.

Another object of the invention is to provide 20 an improved form of ironing apparatus in which the operating structure is built upon a substantially solid base, which base is covered with a finished shroud for ornamental purposes.

Another object of the invention is to provide 25 a novel form of mounting for the buck, and a buck which is so constructed that it is somewhat deformable or resilient so as to aid in equalizing the pressure between the shoe and the buck when a piece of material having portions of 30 unequal thickness is inserted between the shoe and the buck.

Another object of the invention is to provide a novel form of locking mechanism for the arm 35 which carries the movable shoe, and to provide a novel form of connection between the arm and the shoe and through which connection, pressure may be applied to the shoe.

As illustrated in the drawings, the ironer embodying my invention comprises, in general, a rigid base upon which a buck is resiliently mounted, an arm pivoted to the base, a shoe carried by said arm at its swinging end, said arm being adapted to swing or move said shoe from an operative position immediately over the buck 45 to an inoperative position away from the buck, a novel form of locking mechanism for the arm which becomes automatically effective when the shoe is moved into operative position over the buck for locking said arm in position, a pressure 50 applying connection between the arm and the shoe for applying pressure to the shoe, and a lever for operating said pressure applying connection, said lever being also operable for releasing said arm locking mechanism when it is desired to 55 move said shoe away from said buck.

For a better understanding of the invention reference may be had to the accompanying drawings of which there are three sheets, and in which:

Fig. 1 is a plan view of an ironing apparatus 5 embodying my invention;

Fig. 2 is a front elevational view of the apparatus illustrated in Fig. 1;

Fig. 3 is a side elevational view of the ironing apparatus, certain of the parts being broken 10 away to illustrate the operating mechanism of the apparatus, the parts being shown in a position where the shoe is in operative position above the buck but with the pressure released;

Fig. 4 is a side elevational view similar to Fig. 3 15 but illustrating the position which the operating parts assume when the shoe is moving away from the buck;

Fig. 5 is a cross sectional view of the shoe and the buck taken in a plane along the line 5—5 of 20 Fig. 2;

Fig. 6 is a sectional view taken in the plane on the line 6—6 of Fig. 2, looking in the direction of the arrows;

Fig. 7 is a sectional view taken in the plane 25 on the line 7—7 of Fig. 3, illustrating the pressure applying connection between the arm and the shoe;

Fig. 8 is a perspective view of the rigid base; 30

Fig. 9 is a plan view of the panel which forms a part of the buck.

As illustrated in the drawings, the ironing apparatus comprises, in general, a rigid base 10, a buck 12 resiliently supported by the base 10, 35 an arm 14 pivotally mounted at one end thereof upon the base 10, a shoe 16 carried by the swinging end of the arm 14, a lever 18 carried by the arm 14 and operable for controlling the operation of the ironing apparatus, and a shroud 20 providing an ornamental covering for the base 10. 40

The arm 14 may, if desired, be provided with a forwardly projecting handle 22 for convenience in moving the shoe into an operative position over the buck.

The base 10 comprises a pair of relatively heavy side rails 24, each rail being provided at one end thereof with an outwardly extending arm 26, and at the other end thereof, with up-standing arms 28 which may be embossed, as 50 illustrated, for rigidity, the side rails 24 being connected adjacent the forward end thereof by a buck spring plate 30, and adjacent the rear end thereof and between the arms 28 by a cam plate 32, and by another plate 34, which connects the 55

- arms 28 on the forward edge thereof. The base 10 is rigid and may be provided with a plurality of rubber feet 36 carried by brackets 38 secured to the frame 10. The base 10 is covered by the ornamental shroud 20 so as to be concealed thereby and which shroud 20 may be secured to the base 10 in any suitable manner such as by a plurality of stud bolts 40 securing an upturned portion of the shroud 20 to the plate 34 and a pair of brackets 42 secured to the under side of the shroud and bolted to the arms 26. The shroud 20 is provided with a throat portion 44 above the plate 30.
- The buck 12 comprises a panel or plate 50, illustrated in plan in Fig. 9, and is constructed of sheet metal. The panel 50 is elongated and is provided with a generally square corner at one end and with a continuous curved portion at the other end thereof. The panel is provided with a plurality of longitudinally extending ribs 52 for stiffening, and with a rib 54 which extends around the periphery of the plate 50. The ribs 52 are enlarged at the center and are provided with a plurality of bolt holes 56. The edge of the plate 50 is provided with an upwardly extending flange 58 which acts to confine in place a pad 60 which is adapted to be covered by a removable cloth 62. The plate 50 is arched in cross section, as illustrated in Fig. 5, and is supported at the central portion thereof and secured by four bolts 64 which pass through aligned bolt holes in the plate 50 and the plate 30 and through the throat 44 of the shroud 20, the bolts on the under side of the plate being provided with a plurality of nuts and compression springs 65 being disposed about the bolts 64 and between the plates 50 and 30 for resiliently supporting the buck 12. A collar 66 is disposed below the plate 50, the cross section being shaped like the cross section of the throat, and is adapted to close the space between the upper extremity of the throat 44 and the under side of the plate 50. On account of the means by which the buck plate 50 is supported, the buck 12 is capable of movement relative to the frame 10 and is also capable of being displaced from its normal position when unequal pressures are applied to different portions thereof. The buck plate 50 being constructed of sheet metal is resilient and somewhat deformable under load and is capable of a certain amount of twisting due to the application of unequal pressures to different portions thereof and for the purpose of compensating for the effect produced by inserting a piece of material having portions of different thicknesses between the shoe and the buck so that the pressure applied may be more or less uniformly distributed over the entire area of the material confined between the shoe and the buck.
- The arm 14 is channelled or U-shaped in cross section and is curved irregularly but somewhat symmetrically from one end thereof to the other. Adjacent to one end, the arm 14 is mounted upon a shaft 70 which extends between the arms 28 of the frame, and which shaft 70 is secured in place by a pair of screws 72 extending through aligned openings in the side walls of the arm 14 and the arms 28. A sleeve 74 is disposed about the shaft 70 and there is disposed about sleeve 74, a pair of coiled springs 76, one end of each of the coiled springs abutting a flange 78 on the plate 34, and the other end of each of the coiled springs abutting the inside of the arm 14 between the sides thereof for constraining the free end of the arm upwardly.

At the swinging end of the arm 14 and between the sides thereof a shaft 80 is disposed, and which is secured in place by a pair of screws 82 extending through oppositely disposed openings in the sides of the arm 14 and upon which shaft, an eccentric 84 is disposed. A sleeve 86 is disposed about the eccentric and is provided with a depending arm 88 which together constitutes a pressure link. A shaft 90 is carried by the pressure link and extends through slots 92 formed in a pair of lugs 94 and in the sides of the arm 14. The lugs 94 are provided with plates 96 suitably secured to the lugs 94 for preventing the shaft 90 from coming out of the slots 92. The sleeve 86 is provided with a slot, and the lever 18 extends through the slot and is threaded into a threaded opening provided in the eccentric 84. Movement of the eccentric 84 about the shaft 80 will increase or decrease the distance between the shaft 80 and the shaft 90.

The shoe 16 comprises a cast plate 98 which is provided with a surface complementary to that of the buck and together with the buck constitutes the pressing or ironing surface. The lugs 94 are cast integral with the plate 98 and thereby support the shoe from the arm 14. A plurality of heating elements 100 are secured in position against the plate 98 by a pair of arms 102, which are held in position by a bolt 104 threaded into a suitable threaded opening formed in the plate 98. A dished sheet metal panel 106 is provided for covering the upper surface of the shoe and is provided with a transversely extending slot at the middle from one edge thereof to adjacent the opposite edge for receiving the arm 14. The panel 106 may be provided with a plurality of ribs 108 for stiffening the same and the side edges of the panel 106 are disposed within the side edges of the plate 98. On one side of the panel 106 a thermostat dial 110 may be provided for adjusting and controlling the temperature of the heating element, and on the other side of the panel 106, an opening may be provided whereby an electric cord 112 for conducting energy to the heating element may pass to the space 30 40 45 within the shoe 16.

When the arm is in the position illustrated in Fig. 3, if the lever 18 is moved from the position in which it is illustrated in full line to the position in which it is illustrated in dotted line, pressure will be applied to the shoe 16 forcing the same against the buck 12 and against the compression of the springs 65. When the lever 18 is moved from the position in which it is illustrated in full line in Fig. 3 to the position in which it is illustrated in dotted line in Fig. 3, the distance between the shaft 80 and the shaft 90 is increased on account of the fact that the center of the eccentric 84 will be moved downwardly.

In order to apply pressure to the shoe 16 when the same is disposed in operative position against the buck 12, it is necessary that the arm 14, which takes the pressure reaction, be held from moving upwardly. To this end a locking mechanism is provided which becomes automatically effective for locking the arm 14 in the position in Fig. 3, when the shoe is moved down into operative position against the buck 12. This locking mechanism comprises a shaft 120 carried by the arm 14 and extending between the sides thereof, a locking cam 122 carried by the shaft 120, a spring 124 coiled about the shaft 120 and constraining the locking cam 122 toward the position in which it is illustrated in Fig. 3, and a locking surface 126 formed on the plate 32 and 75

which cooperates with the locking cam 122 for holding the arm 14 in the position illustrated in Fig. 3 until released. The reaction to the application of pressure to the shoe is then taken 5 through the shaft 70 and the locking cam 122 by the base member.

When it is desired to move the arm 14 from the position in which it is shown in Fig. 3 to the position in which it is shown in Fig. 4, it is necessary to release the locking cam 122 from engagement with the cam surface 126, and to this end, a linkage connection is provided between the cam 122 and the lever 18 which operates when the lever 18 is moved backwardly to its 10 extreme position (or to the left from the position in which it is shown in Fig. 3) to move the cam 122 to the position in which it is illustrated in Fig. 4. The release mechanism for the locking cam comprises a link 130 pivoted at one end 15 thereof to the cam 122 and at the other end thereof to a bell crank 132, the bell crank 132 being pivoted upon a bracket 134 carried by the arm 14 internally thereof, a second link 136 pivoted at one end thereof to the bell crank 132, and 20 at the other end thereof, to an arm 138 carried by the shaft 80, and a pin 140 carried by the eccentric 84 upon one side thereof which is engageable with a portion of the arm 138 for moving the same in a counter clockwise direction about 25 its pivot as viewed in Figs. 3 and 4.

The locking cam 122 is provided with a shoulder 142 which is engaged by a latch bar 144 pivoted on the arm 14, the latch bar being U-shaped, and which latch bar is held in place by a bracket 30 146 carried by the arm 14. After the locking cam 122 has been released by moving the lever 18 in a counter clockwise direction as far as possible, the latch bar 144 will engage the shoulder 142 of the locking cam 122 and hold the same 35 in a position illustrated in Fig. 4, until the arm 14 swings upwardly sufficient for the end 148 of the latch bar to engage the flange 78 of the plate 34 and lift the latch bar free from engagement with the shoulder 142 of the locking cam 122, 40 whereupon the locking cam will be constrained by the spring 124 back toward its normal position in which it is illustrated in Fig. 3. When the arm 14 is again moved downwardly to a position where the shoe 16 is disposed against the 45 buck 12, the cam 122 will lock against the cam surface 126 and hold the arm in such position so that pressure may be applied to the shoe 16 by operation of the lever 18.

The movement of the shoe 16 away from the buck enables an operator of the machine to place a piece of material upon the buck to be pressed without hindrance from the shoe, and after the material is placed upon the buck, the shoe 16 50 may be moved into engagement with the material by moving the arm 14 downwardly which may be accomplished through the intermediary of the handle 22. Thereafter operation of the lever 18 in a clockwise direction, looking at Figs. 3 and 55 4, will separate the arm 14 from the shoe 16 thereby applying pressure to the shoe and the buck 12 against the compression of the springs 60 65 and the resiliency of the backing plate 50 of the buck. After the material has been pressed 70 or ironed, movement of the lever 18 in a counter-clockwise direction from the position in which it is illustrated in dotted line in Fig. 3 to the position in which it is illustrated in full line in Fig. 3, will release the pressure between the shoe 75 and the buck and further counterclockwise move-

ment of the lever 18 will cause the pin 140 carried by the eccentric 84 to engage the upstanding portion of the lever 138 for operating the linkage to lift the locking cam 122 free from engagement with the locking surface 126.

The heating elements 100 in the shoe 16 preferably are covered with insulating material to prevent the cover 106 thereof from becoming heated. The cam 122 is adapted to lock with the cam plate 32 in a plurality of positions to 10 permit different materials varying widely in thickness to be pressed between the shoe 16 and the buck 12.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. In an ironer, a base, a buck resiliently supported thereby, an arm pivotally supported by said base, a shoe carried by said arm and cooperable with said buck, said arm being adapted for movably supporting the shoe in an operative position over said buck and in an inoperative position away from said buck, means adapted for automatically locking said arm, upon moving said shoe to an operative position over said buck, in any one of a plurality of positions wherein the shoe is contiguous to but spaced from the buck to permit materials varying widely in thickness to be pressed between said shoe and said buck, and means for applying pressure to said shoe when the same has been moved into an operative position over said buck.

2. In an ironer, a base, a buck supported thereby, a shoe movably supported upon said base and cooperable with said buck, said buck including a substantially horizontally disposed backing plate supported intermediate the ends thereof, said backing plate being deformable under a pressure within the range of the pressure applied to the buck by the shoe, and means for applying pressure to said shoe.

3. In an ironer, a base, a buck supported thereby, a vertically movable arm pivoted adjacent one end to said base, a shoe, an adjustable connection between the other end of said arm and said shoe, said arm being adapted to support said shoe in an operative position contiguous to said buck and in an inoperative position away from said buck, means effective for locking said arm in any one of a plurality of positions and against upward movement when said shoe is in operative position, and other means operably associated with said adjustable connection whereby said shoe may be moved relative to said arm for applying pressure to said shoe.

4. In an ironer, a base, a buck supported thereby, a vertically movable arm pivotally supported adjacent one end thereof by said base, a shoe, an adjustable connection between the other end of said arm and said shoe, said arm being adapted to support said shoe in an operative position contiguous to said buck and in an inoperative position away from said buck, means effective upon moving said shoe into operative position for locking said arm in any one of a plurality of positions and against upward movement, a lever operably associated with such adjustable connection whereby said shoe may be

- moved vertically relative to said arm for applying and releasing pressure upon said buck, and a connection between said lever and said arm locking means whereby the same may be released to permit said arm to move upwardly for moving said shoe away from said buck.
5. In an ironer, a base, a buck supported thereby, a vertically movable arm pivotally supported adjacent one end thereof by said base, a shoe carried by said arm at the other end thereof, said arm being adapted to support said shoe in an operative position over said buck and in an inoperative position away from said buck, means effective upon moving said shoe into operative position for locking said arm in any one of a plurality of positions and against upward movement, means including a lever for applying pressure to said shoe when the same is in an operative position, and a connection between said arm locking means and said lever whereby said lever may be operated for releasing said arm locking means.
6. In an ironer, a shoe member, a buck member, means for resiliently supporting one of said members, means for supporting one of said members for swinging movement toward and away from the other of said members, means for locking said members in any one of a plurality of positions and contiguous to each other, means including a lever for applying pressure to said members when the same are contiguously disposed, and a connection between said lever and said locking means whereby said locking means may be released for moving said members away from each other.
7. In an ironer including a buck, a shoe, a swinging arm for supporting said shoe for movement toward and away from said buck, means for locking said arm with respect to said buck when the shoe and buck are adjacent one another, an adjustable connection between said shoe and said arm comprising a shaft carried by said arm, an eccentric on said shaft, a sleeve carried by said eccentric, means for securing said sleeve to said shoe so as to permit swiveling action of said shoe, and a lever connected to said eccentric.
8. In an ironer, a base, a buck supported thereby, a swinging arm pivoted adjacent one end thereof to said base, said arm being channel-shaped in cross section, a shoe cooperable with said buck and having a recess in the top surface thereof for accommodating one end of said arm, a connection between said shoe and said last mentioned end of the arm for enabling the swiveling of said shoe, means effective for locking said arm in position to hold said shoe against said buck, and means for releasing said locking means, said connection between said shoe and said arm, said releasing means and said locking means being housed and concealed within said arm.
9. In an ironer, a base comprising a pair of spaced side rails, means including a cam plate for rigidly connecting said side rails, a buck supported upon said side rails, an arm pivotally supported by said base, a shoe carried by said arm, said arm being adapted to move said shoe from an operative position adjacent said buck to an inoperative position away from said buck, means constraining said arm so as to move said shoe away from said buck, a locking cam carried by said arm and engageable with said cam plate upon moving said shoe into operative position for locking the shoe end of said arm against upward movement, and means for operating said locking cam to disengage the same from said cam plate.
10. In an ironer, a base comprising a pair of spaced side rails, means including a cam plate for rigidly connecting said side rails, a buck supported upon said side rails, an arm pivotally supported by said base, a locking cam engageable with said plate, a shoe carried by said arm, said arm being adapted for moving said shoe from an operative position adjacent said buck to an inoperative position away from said buck, means constraining said arm so as to move said shoe away from said buck, means for releasing said locking cam from engagement with said plate, and a latch engageable with said locking cam for holding the same out of engagement with said cam plate until the shoe end of the arm approaches the end of its upward travel.
11. In an ironer, a base comprising a pair of spaced side rails, means for rigidly connecting said side rails, a locking member carried by said side rails, a buck supported upon said side rails, an arm pivotally supported by said base, a shoe carried by said arm and cooperable with said buck, said arm being adapted to support said shoe for movement from an operative position adjacent to said buck to an inoperative position away from said buck, means constraining said arm so as to move said shoe away from said buck, a locking element carried by said arm and engageable with said locking member upon moving said shoe into position adjacent said buck for locking said arm against upward movement, means for operating said locking element to disengage the same from said locking member when it is desired to move said shoe away from said buck and a latch engageable with said locking element for holding the same out of operative engagement with said locking member until the shoe end of said arm approaches the end of its upward travel.
12. In an ironer, including a buck, a shoe, a swinging arm for supporting said shoe for movement toward and away from said buck, an adjustable connection between said shoe and said arm comprising a shaft carried by said arm, an eccentric on said shaft, a sleeve carried by said eccentric, means for securing said sleeve to said shoe, said means comprising a shaft adapted to permit said shoe to have a universal movement with respect to said sleeve, and a lever connected to said eccentric.
13. In an ironer, a rigid base, a buck supported on said base, a locking member carried by said base, an arm pivotally supported by said base, a shoe suspended from said arm and cooperable with said buck when said arm is moved about its pivot in one direction, means opposing the movement of said arm in said direction, said arm having a locking element engageable with said locking member for locking said arm against movement in a direction opposite to said first mentioned direction, means for disengaging said element from said member when moving said arm in said opposite direction, and a catch for said element operable for maintaining said arm out of engagement with said locking member.
14. Ironing apparatus comprising an ironing element, a support for said ironing element and means for relatively moving said element and support including a first shaft mounted in said support, a second shaft mounted in said element, and an extensible connection between said second

shaft and said first shaft, said second shaft being guided for movement by slots in said support.

15. Ironing apparatus in which an arm and a base are pivotally connected, a buck and a shoe carried by said arm and base in cooperable relationship, means to rotate the arm about said pivot to move the shoe and buck into and out of iron-

ing relationship, means to lock the arm against rotation about said pivot in any one of a plurality of angular relationships between the arm and base, and means to apply pressure between the buck and shoe while the arm and base are so locked.

THEODORE R. BUSH.
